UNITED STATES PATENT OFFICE.

ARTHUR M. GODWIN, OF GRAND RAPIDS, MICHIGAN, ASSIGNOR TO WOLVERINE BUMPER & SPECIALTY COMPANY, OF GRAND RAPIDS, MICHIGAN, A CORPORATION OF MICHIGAN.

DESIGN FOR A BUMPER FOR VEHICLES.

Application filed June 26, 1924. Serial No. 9,978. Term of patent 3½ years.

To all whom it may concern:

Be it known that I, ARTHUR M. GODWIN, a citizen of the United States, residing at No. 636 Fountain Street NE., Grand Rapids, in the county of Kent and State of Michigan, have invented a new, original, and ornamental Design for Bumpers for Vehicles, of which the following is a specification, reference being had to the accom-

panying drawings, forming a part thereof, in which—

Figure 1 is a top plan view of a bumper for vehicles showing my design; and

Figure 2 is a face view thereof.

I claim:

The ornamental design for a bumper for vehicles substantially as shown.

ARTHUR M. GODWIN.
